UNITED STATES PATENT OFFICE.

DAVID J. HAUSS, OF CINCINNATI, OHIO.

DESIGN FOR AN INCANDESCENT LAMP.

SPECIFICATION forming part of Design No. 18,098, dated February 21, 1888.

Application filed January 6, 1888. Serial No. 260,020. Term of patent 7 years.

To all whom it may concern:

Be it known that I, DAVID J. HAUSS, of Cincinnati, in the county of Hamilton and State of Ohio, have invented a new and useful Design for Incandescent Lamps, which design is fully set forth in the following specification and accompanying drawing, in which the accompanying figure represents a side view of the design.

10 This design consists in the peculiar shape and configuration of all the parts, as will now be set forth and explained, reference being had to the accompanying drawing, in which—

15 A represents the upper part, which is rectangular in shape, while immediately below this is the part B, the outline of which curves or slopes inwardly until it meets the part C, when the outline flares slightly outward. These lines relate to the holder. The exterior lines 20 of the bulb D and the holder, as shown at E E, unite or join on the same curve, while the sides from F to G form the segment of a circle,

and the lower end of the bulb from H to I approximately forms a semicircle, except at the extreme lower end, which terminates to a 25 point, J, and surrounding this point is an annular depressed portion, K.

What I claim as new is—

The design for an incandescent electric lamp herein shown and described, wherein the exterior lines of the lower half of the holder and the upper half of the bulb merge into each other on a depressed circular line, the lower end of the bulb being semicircular in form, having at the extreme end a projecting point, 35 and surrounding the point an annular depression, substantially as herein set forth.

In testimony that I claim the foregoing I have hereunto set my hand, this 30th day of November, 1887, in the presence of witnesses. 40

DAVID J. HAUSS.
